UNITED STATES PATENT OFFICE.

JOSEPH MARTYNA, OF OIL CITY, PENNSYLVANIA.

PARACHUTE.

1,277,980.

Specification of Letters Patent.

Patented Sept. 3, 1918.

Application filed April 29, 1918. Serial No. 231,346.

To all whom it may concern:

Be it known that I, JOSEPH MARTYNA, a subject of the Emperor of Austria, having declared my intention to become a citizen of the United States of America, residing at Oil City, in the county of Venango and State of Pennsylvania, have invented certain new and useful Improvements in Parachutes, of which the following is a specification.

around the canopy 11 to which are secured transverse braces 14 attached to the top bar 12 at their points of jointure with the upright bars 15 of the frame. The canopy 11 arches slightly from the braces 14 to the opposite free ends 23 thereof forming intermediate arcuate sections or portions 24 adapted for catching or pocketing air during the operative downward flight of the 65 parachute when in use.

Anchor pieces 16 are carried by the lower bar 17 of the upper portion of the frame 10, suitably connected to the canopy 11 at a point adjacent the opposite ends thereof by 70 means of cords 18. Springs 19 are preferably positioned for connecting the cords 18 together and it will be understood that the canopy 11 is normally maintained outstretched with the frame 10 centrally depending therefrom.

The device is adapted to be mounted upon a person's back with the crosspiece rod 17 adjacent the shoulders while straps 20 secured to the rod 17 adjacent its point of 80 connection with the pieces 16 are adapted to be secured to the arms of the wearer. A belt 21 at the lower end of the upright rods 15 of the frame 10 is adapted to be tightly secured around the wearer's waist while a 85 strap 23 also mounted upon the bars 15 is adapted to encompass the chest of the wearer.

From this detailed description of the device, the manner of attaching the same to a 90 person will be apparent while a person dropping through the air will be supported by the canopy 11 to slowly and safely descend to the ground beneath. While the structure 95 possesses great strength, the same is light in weight and can be readily worn without interfering with the use of the arms and legs of the aviator in managing the air craft while the personal safety of the aviator is insured.

100 What I claim as new is:—

1. A parachute comprising a T-shaped frame, cross braces upon the frame, an elongated canopy mounted on top of the frame secured to said cross pieces and having 105 curved end portions, stay cords for the opposite ends of the canopy, arm-encircling straps carried by the top portion of the frame, and body-encircling straps carried by the upright portion thereof.

110 2. A parachute comprising a T-shaped frame formed of bars, transverse braces car-

ried by the top bar of the frame, an elongated canopy centrally positioned upon the top of the frame secured to said braces and having upwardly curved portions from the 5 said braces to the opposite free ends of the canopy, attaching pieces secured to the bottom bar of the top portion of the frame, cords connected between said pieces and

points adjacent the opposite ends of the canopy, spring connections between the said 10 cords, and straps secured to the frame adapted for mounting the device upon the back of a person.

In testimony whereof I affix my signature.

JOSEPH MARTYNA.

Copies of this patent may be obtained for five cents each, by addressing the "Commissioner of Patents, Washington, D. C."
